J. L. POWER.

ADJUSTABLE PORTABLE ELECTRIC LIGHT SUPPORT OR BASE.

APPLICATION FILED SEPT. 14, 1914.

1,162,394.

Patented Nov. 30, 1915.

UNITED STATES PATENT OFFICE.

JOHN L. POWER, OF TRENTON, NEW JERSEY.

ADJUSTABLE PORTABLE ELECTRIC-LIGHT SUPPORT OR BASE.

1,162,394.

Specification of Letters Patent. Patented Nov. 30, 1915.

Application filed September 14, 1914. Serial No. 861,579.

To all whom it may concern:

Be it known that I, JOHN L. POWER, a citizen of the United States, residing at 874 Stuyvesant avenue, Trenton, in the county of Mercer and State of New Jersey, have invented new and useful Improvements in Adjustable Portable Electric-Light Supports or Bases, of which the following is a specification.

My invention relates to improvements in portable electric light supports or bases, in which it is possible to change the angle or position of the light by movement of the socket pipe in the main support or base, by means of pulling the socket pipe from the support or base and re-placing it in one of the three holes within the elongated slot, which affords facilities for the proper adjustment of the light independently of the base, without the releasing or tightening of a spring by means of a thumb screw, or otherwise.

A still further object of my invention, is to provide a device which can be employed for the support of the lamp on a flat surface or projecting objects, which can be attached to projecting objects or pieces of furniture by means of a forward and reverse clamp or by hanging against perpendicular objects.

The accompanying drawing illustrates my application for my invention.

Figure 1, is a side view of the lamp support or base in connection with the connecting fixture and electric lamp shade, C: Fig. 2 is the section view of the socket pipe which is shown in connection with Fig. 1, as B: Fig. 3 is a side view of the lamp support or base clamped to a projecting object: Fig. 4, is a side view of the lamp support or base clamped in a reversed position to a projecting object, thus Fig. 3 and Fig. 4, shows a forward and reverse method of clamping: Fig. 5, is a side view of the lamp support or base attached to a perpendicular object: Fig. 6, section 1, is a section view of the main support or base, representing the front section, Fig. 7 section 2, is a section view of the main support or base, representing the rear section.

Referring to the drawing Fig. 6 section 1 and Fig. 7 section 2, designating the lamp support or base member preferably stamped or cut of spring metal, 1 and 2 as shown in Fig. 6 and Fig. 7, is properly curved to constitute a forward and reverse clamping member, so as to provide two methods of

clamping to projecting objects or pieces of furniture, as shown in Fig. 3 and Fig. 4.

3, in Fig. 6 section 1 and Fig. 7 section 2, represents the center member properly punched with the elongated slot E into which is entered the socket pipe B, as shown in Fig. 1 and forms the adjustable connecting means, designated, securing the lamp to its support or base. The socket pipe B Fig. 1, or adjustable connecting means, as shown by D in Fig. 2, is properly ridged on each side so as to fit in the elongated slot E, Fig. 6 section 1, and Fig. 7 section 2, and may be raised or lowered in the support or base in three different positions as shown by notches a, b, and c, on each side of the socket pipe B, as in Fig. 1. The socket pipe B is externally threaded and is made fast to collar of lamp socket C. A, in Fig. 1, represents the electric wire or cord passing through the hole F, as shown in Fig. 7, section 2, for the purpose of obtaining sufficient slack of the electric wire or cord as designated in Fig. 1 to make easy the adjustment of the socket pipe B.

By the illustration in drawing it will be noticed that the lamp may be adjusted to three (3) different positions in the support or base, relative to the three (3) holes in the elongated slot by withdrawing the socket pipe or connecting means and re-entering in one of the other of the three (3) holes, and further changes of position of the lamp may be obtained by raising or lowering the socket pipe or connection means and securing it in one of the three (3) notches a, b, and c, Fig. 1.

What I claim is:

1. An electric lamp support or base comprising two members bent in a forward and reverse curve, or otherwise, to form bearing points, and a third member of said lamp support or base slotted with an elongated slot with three holes within said elongated slot and a socket pipe or an adjustable lamp connecting means ridged on either side and fitted with three notches, entered in one of the three holes, and made fast to the support or base by resting in one of the three notches.

2. An electric lamp support or base comprising two members bent to clamp on objects in a forward and reverse manner and a third member slotted with an elongated slot with three holes within said slot with a socket pipe or connecting means entered

in one of the three holes forming an adjustable means which can easily be made by pulling the socket pipe or connecting means from the holes within the elongated slot 5 allowing the electric wire or cord to pass from one hole to the other through the elongated slot for the purpose of reentering the socket pipe in the hole desired.

3. An electric lamp support or base having a member slotted with an elongated slot 10 with three holes within the slot placed at a desired distance from each other and a socket pipe or an adjustable lamp connecting means ridged on either side fitted with 15 three notches entered in one or the other of the holes and with a fourth hole of like size

and placed at a desired distance from the elongated slot for the purpose of receiving the electric wire or cord and allowing sufficient slack in same before passing through the socket pipe or connecting means, making the withdrawal and entry of the socket pipe or connecting means easy and without the loosening or tightening of a spring tension or other adjustable spring controlled 20 connecting means coöperating with the slotted member. 25

JOHN L. POWER.
